US0D1097836S

(12) **United States Design Patent** (10) **Patent No.:** **US D1,097,836 S**
(45) **Date of Patent:** **** Oct. 14, 2025**

(54) **SENSOR FOR DETECTING METAL**

(71) Applicant: **Proceq AG**, Schwerzenbach (CH)

(72) Inventors: **Marcel Poser**, Oberuzwil (CH);
Michael Geiser, Zürich (CH); **Thomas Knorr**, Efringen-Kirchen (CH); **Jonas Zolliker**, Dübendorf (CH); **Wai-Loong Lim**, San Francisco, CA (US); **Eric Nichols**, San Francisco, CA (US)

(**) Term: **15 Years**

(21) Appl. No.: **35/518,071**

(22) Filed: **Aug. 17, 2022**

(80) **Hague Agreement Data**

Int. Filing Date: **Aug. 17, 2022**

Int. Reg. No.: **DM/223569**

Int. Reg. Date: **Aug. 17, 2022**

Int. Reg. Pub. Date: **Aug. 18, 2023**

(51) **LOC (15) Cl.** **10-04**

(52) **U.S. Cl.**

USPC **D10/78; D10/47**

Primary Examiner — Christian P. McLean

Assistant Examiner — Sara S Sahneh

(57) **CLAIM**

The ornamental design for sensor for detecting metal as shown and described.

DESCRIPTION

4. Sensor for detecting metal

4.1: Perspective

4.2: Top

4.3: Bottom

4.4: Back

4.5: Front

4.6: Left

4.7: Right

4.8: Perspective

The broken lines illustrate portions of the sensor for detecting metal that form no part of the claimed design.

1 Claim, 8 Drawing Sheets
